Specification for Design.

Patented Feb. 23, 1915.

Application filed November 11, 1914. Serial No. 871,835. Term of patent 3½ years.

To all whom it may concern:

Be it known that I, RAY G. NELSON, a citizen of the United States, and resident of the city of Seattle, county of King, and State of Washington, have invented a new, original, and ornamental Design for Pipes, of which the following is a specification, reference being had to the accompanying drawing, which forms a part thereof.

Figure 1 is a top view of the pipe; Fig. 2 is a side view of the pipe; Fig. 3 is a larger

scale side view of the bowl section of the pipe; Fig. 4 is a large scale view of the bowl section taken from a quartering position.

What I claim is:

The ornamental design for a pipe, as shown.

RAY G. NELSON.
